UNITED STATES PATENT OFFICE.

WILLIAM J. GREENMAN, OF CORTLAND, NEW YORK.

EXTENSIBLE WINDOW-SCREEN.

SPECIFICATION forming part of Letters Patent No. 700,638, dated May 20, 1902.

Application filed February 25, 1899. Serial No. 706,777. (No model.)

To all whom it may concern:

Be it known that I, WILLIAM J. GREENMAN, a citizen of the United States, residing at Cortland, in the county of Cortland and State of New York, have invented certain new and useful Improvements in Extensible Window-Screens; and I do hereby declare the following to be a full, clear, and exact description of the invention, such as will enable others skilled in the art to which it appertains to make and use the same.

My invention relates to window or door screens in general, but more particularly to that class of screens commonly termed "extensible" screens; and it consists of two sections adapted to slide one upon the other, each section having oppositely-faced grooves or channels in which rollers are placed to provide for an easy and frictionless sliding movement of the sections.

The invention further consists of the general arrangement and combination of the several parts, as will be hereinafter fully described, and particularly stated in the claim.

In the class of extensible screens, particularly those in which one section is designed to slide or move upon the other, great objection arises from the fact that the construction is such as to produce unnecessary friction and binding of the parts, often necessitating a careful adjustment of the same; and one of the essential objects of my invention is to overcome this objection, and this I do by providing for an easy, uniform, and comparatively frictionless sliding movement of the two sections, free from all tendency to bind or stick. This and other objects of the invention are obtained by the means illustrated in the accompanying drawings, in which—

Figure 1 is a perspective view of my improved window-screen, showing parts of the section broken away; Fig. 2, a vertical section on line 2 2 of Fig. 1, and Fig. 3 is a longitudinal section on line 3 3 of Fig. 1.

In the several views the numerals 1 and 2 indicate the respective sections, each of which is composed of an outer end piece 3 and side pieces 4, joined together at their ends in any suitable manner, preferably by an open mortise and tenon, as shown in the drawings. The

usual inner end piece is dispensed with, and in lieu thereof a thin strip of metal bent longitudinally upon itself is employed to connect the inner ends of the side pieces together and to form a clamping-strip 5, in which to 55 secure the inner edge of the wire-netting. This clamping-strip is placed a short distance from the inner end of the section, and the edge of the netting is secured between the folds thereof, the sides and other edge of the netting being secured to the section in the usual manner. The outer edge of the netting is covered by a strip 6, which protects said edge from injury and serves as a filling-piece to make the sides of the end piece flush with the 65 face of the side pieces. The inner face of the side pieces of each section is provided with corresponding longitudinal grooves or channels 7 of any suitable shape, preferably angular, and in said grooves or channels are 70 placed rollers 8, said rollers being of a size sufficient to produce a slight separation between the two sections. The rollers are preferably arranged to freely travel in the oppositely-faced grooves in the sections, thereby 75 affording an easy and smooth sliding movement to the sections one upon the other. Stops 9 are arranged at a suitable distance apart at the outer ends of the grooves to limit the travel of the rollers and to prevent them 80 dropping or rolling therefrom. The sections are held in their slidable position by means of hook-guides 10 and 11, the guides 10 being secured to the side edges of the section 2 and hooking over the side edges of section 1 and 85 the guides 11 being secured to the side edges of section 1 and hooking over the side edges of section 2. These guides are so arranged and fixed on the respective sections that they also serve as stops to limit the extensible 90 movement of the sections.

It will be understood that the rollers may be either of wood or metal, wooden rollers being much the preferable in some respects, as they are cheaply made and do not blacken the 95 runs or grooves.

Having thus fully described my invention, what I claim, and desire to secure by Letters Patent, is—

An article of manufacture, an extensible 100

window-screen consisting of two sections slid-
ably connected together, one upon the other, |
said sections having grooves in the inner ad-
jacent faces of the side rails, registering with
5 each other, rollers loosely arranged in said
grooves, and stops for retaining the rollers in
the grooves.

In testimony whereof I affix my signature
in the presence of two witnesses.

WILLIAM J. GREENMAN.
